Application October 21, 1947, Serial No. 781,028

11 Claims. (CL 169—2)

1 This invention relates to mobile fire extinguishing apparatus and more particularly to equipment for such an apparatus for applying fire extinguishing mediums.

This application is a continuation-in-part of my copending application entitled Fire Extinguishing Apparatus, Serial No. 654,333, filed March 14, 1946, now abandoned.

The fire fighting apparatus with which the invention is concerned is generally disclosed and claimed in Patent 2,352,379, issued to Eric Geertz, on June 27, 1944. In that patent is disclosed a power driven truck which is provided with facilities for carrying its own supply of fire extinguishing mediums and devices for applying said mediums onto the fires to be extinguished. One of the most important functions that must be performed by this type of fire fighting apparatus is to extinguish ground fires resulting from the ignition of spilled inflammable fluids.

It is the primary object of this invention to provide improved equipment for more effectively applying fire extinguishing mediums to ground fires.

With the discharge equipment of the present invention, fires which are burning upon the ground over which the truck must pass are extinguished so that a way is cleared for the passage of the truck. This is important because in the case of a crashed airplane, for example, gasoline usually is spilled and thrown over the ground for a considerable distance away from the airplane, and if this gasoline becomes ignited, it is apparent that the passage of the truck through the flames would be dangerous. With the present invention, a wide path is cleared through the fire in advance of the truck so that the truck and its occupants may approach the fire with safety.

Moreover, when the crashed airplane is reached, it is usual that a considerable ground fire is present because of the burning of the gasoline which has escaped from the fuel tanks. If this ground fire is beneath the airplane, it is important that the apparatus, which is to direct the fire extinguishing mediums upon this fire, be located close to the ground so that the discharged mediums will be projected beneath the airplane.

Another object of the invention is to provide ground fire extinguishing discharge equipment with means for automatically oscillating the same so that the discharge will cover a greater area. This has been found to be important in accordance with the present invention, because a highly concentrated discharge of the fire extinguishing mediums is necessary to so extinguish a fire that a "flash-back" will not occur.

By having a highly concentrated discharge delivering a large volume of appropriate fire extinguishing mediums over a limited area during a given instant, the fire in that area is perma-

nently extinguished and by oscillating this concentrated discharge back and forth, the fire burning over a large area is likewise permanently extinguished. By employing power driven means for oscillating the discharge apparatus, it is not necessary for an occupant of the vehicle to manually accomplish this constant movement of the discharge apparatus.

2 A further object of the invention is to provide the discharge equipment with means for automatically stopping the discharge of the extinguishing mediums and the oscillations of the equipment after a predetermined period. This is important to prevent a continuous discharge of the fire extinguishing mediums beyond the need for them to extinguish the fire. By having an automatic means for terminating the supply of fire extinguishing mediums to the discharge apparatus which effects extinguishment of ground fires, this type of discharge will take place only for a limited time. If a further discharge is necessary to extinguish the fire, the attendant has merely to again set into operation this timed discharge of the fire extinguishing mediums.

A preferred embodiment of the invention is disclosed in the accompanying drawings in which:

30 Figure 1 is a side elevational view of the forward part of a fire extinguishing truck to which the equipment of the present invention has been applied, portions being broken away to show the construction of the equipment of the invention.

35 Figure 2 is a plan view of the equipment of the invention.

Figure 3 is a sectional view on line 3—3 of Figure 2.

Figure 4 is a sectional view on line 4—4 of Figure 2.

40 Figure 5 is a sectional view on line 5—5 of Figure 2, and

Figure 6 is a sectional view similar to Figure 5, but of a modified structure.

The truck to which the invention has been applied includes a framework having longitudinal side bars, one of which is shown at 6 in Figure 1. The forward wheels 7 are supported from these side bars, in any conventional manner. Attached to a cross bar 6a is a swivel-joint pipe connection 8, to which liquid carbon dioxide is supplied through a conduit 9. Conduit 9 has therein a valve 10 which is employed to control the flow of the carbon dioxide from a tank carried by the truck in the manner disclosed in the above-mentioned Patent 2,352,379. The carbon dioxide, preferably, should be maintained at a low temperature, and its corresponding low vapor pressure, as is set forth in that patent.

60 Supported by the swivel connection 8 is a

pipe 12. At the entry of pipe 12 into the swivel connection 8 is a packing joint to prevent the escape of liquid and this packing joint permits oscillating motion of the pipe 12 about its axis. It will be noted that the axis of the pipe 12 extends in a substantially vertical direction.

A carbon dioxide discharge nozzle 13 is connected to and supported from the pipe 12 by an elbow coupling 14. This elbow coupling 14, preferably, has a forward portion which is angularly disposed so as to direct the nozzle 13 forwardly and slightly downwardly toward the ground, as appears from Figure 1.

A preferred form of nozzle 13 is disclosed and claimed in the H. V. Williamson Patent No. 2,357,039, dated August 29, 1944. As is explained in that patent, this discharge nozzle serves to cause segregation and separation of the snow and the vapor which are formed by the sudden release of the liquid carbon dioxide. These segregated and separated snow and vapor components are discharged from the nozzle in distinct zones with the snow centrally located of the discharge stream as a core surrounded by the carbon dioxide vapor. The patent points out that this type of discharge is desirable because the enveloping sheath of carbon dioxide vapor tends to prevent the sublimation of the carbon dioxide snow before it has reached the fire, and for the further reason that snow concentrated in one portion of the discharge stream will carry a greater distance. It is possible, however, in practicing the present invention to employ a discharge nozzle of a different character.

The invention contemplates the additional provision of a device for discharging a different fire extinguishing medium upon the ground in conjunction with the carbon dioxide delivered by the nozzle 13. For example, the discharge pipes 15 may be associated with the nozzle 13 for the delivery of mechanical foam in conjunction with the carbon dioxide. It is to be understood, however, that the invention is not limited to the discharge of mechanical foam, for chemical foams can be employed.

The materials to form the foam may be delivered to the pipes 15 through the flexible conduit 16 and a common connecting pipe 17. The delivery of the foam producing materials from the connecting pipe 17 into the discharge pipes 15 will ordinarily be through aspirator sections 18 which will suck air into the fluid being delivered to the pipes 15. The air which is drawn into and mixed with the foam materials will produce the characteristic foam so that upon discharge from the pipe 15 it will be of the proper consistency. This foam not only assists in putting out the fire, but it also forms a covering layer or blanket over the area to which it is applied and thereby prevents flash-back.

The flexible conduit 16 receives the foam producing materials through a control valve 19. A conduit 20 leads from the valve 19 to facilities carried by the truck for supplying the foam-making materials under a suitable pressure head to cause discharge of the materials when valve 19 is opened.

To oscillate the nozzle 13 and the discharge pipes 15, a boss 21 is attached to the elbow 14 and extends upright therefrom. Projecting upwardly from the boss 21 is a pin 22 which passes through the end of a piston rod 23. The piston rod 23 is attached to a piston 24 which may move back and forth within a cylinder 25 hav-

ing closed ends. At the end of the cylinder through which the piston rod 23 passes is a packing gland 26.

To the other closed end of the cylinder 25 is attached a web plate 27 which is pivotally connected by means of a pin 28 to spaced supporting plates 29 which project from a transverse member 30 of the truck framework. This pivotal connection at 28 permits oscillating movement of the cylinder 25 to accommodate arcuate motion of the boss 21 as it oscillates about the axis of the vertical pipe 12.

At opposite ends of the cylinder 25 are port openings to which the flexible conduits 31 and 32 are connected. These flexible conduits 31 and 32 lead to a control valve 33 of the snap action rotary type for controlling the admission of liquid to the opposite ends of the cylinder and also the escape of the liquid from the cylinder ends.

The valve 33 also has connected thereto a supply pipe 34 and a discharge pipe 35. The places of connection of the pipes 34 and 35 to the valve 33 are at points diametrically opposite from each other and at points a quarter turn from the connections to the valve 33 of the flexible conduits 31 and 32 from the cylinder 25. The rotary plug 36 within the valve 33 contains two arcuate-shaped passageways 37 and 38. When the plug 36 is in one position the supply conduit 34 may deliver fluid through the passageway 38 and through the flexible conduit 31 to one end of the cylinder to force the piston in one direction. The fluid on the opposite side of the piston is forced outwardly through the conduit 32 and through the passageway 37 into the discharge pipe 35. When the plug 36 is in the other position, the opposite relationship is established so that the liquid from pipe 34 is delivered through the flexible conduit 32 to the other side of the piston to force it in the opposite direction.

To operate the plug 36 so as to cause continuous reciprocating movement of the piston 24, the plug 36 has a crank arm 39 connected to it by the shaft 40. Stops 41 and 42 mounted on the housing 33 limit the travel of the crank arm 39 to an angle commensurate with that angle necessary for the flow of fluid through the passageways 39 and 40. A rocker arm 43 is pivotally connected to the shaft 40. A spring 44 extends from arm 39 to arm 43 so that the reciprocating motion of arm 43 causes the spring 44 to pass a point diametrically opposite the connection of spring 44 and arm 39. The spring 44 being in tension causes the arm 39 to move rapidly between stops 41 and 42 as the direction of the tensile force changes with respect to the stops 41 and 42. A connecting link 45 is pivotally connected to arm 43 and by a ball and socket joint 45a to the pin 23 which projects upwardly from the elbow 14. As a consequence of this connection, the plug 36 will be oscillated back and forth by the movement of the piston 24 so that it will not be necessary for the attendant to cause this continuous motion of the nozzle 13 and pipes 15.

The fluid which is delivered to pipe 34 to cause reciprocation of the piston 24 may be oil which is delivered under pressure by the oil pump in the truck motor. The delivery of such oil through the pipes 34 is controlled by a manually operable valve 46.

To operate the valve 46 a handle 47 is connected thereto. This handle should extend upwardly into the cab of the truck so that it can be

readily grasped by the attendant. As a further feature of the invention, it is intended that this single handle 47 control the opening and closing of the several valves 10, 19 and 46 so that when the nozzle 13 and supply pipes 15 are set into oscillation, the fire extinguishing fluids will simultaneously be supplied to them. In like manner, when the supply of fluid is shut off by closing the supply valves, it is intended that the oscillations be stopped by this movement of a single operating lever. To accomplish this simultaneous operation, it is intended that the several valves 10, 19 and 46 have their axes substantially in alignment with each other so that they may be interconnected by shafts 48 and 49. If found desirable, universal joints may be located in the shafts 48 and 49 to accommodate any disalignment of the axes of the valves.

It has been stated that the invention also contemplates the provision of means for automatically shutting off the supply of fire extinguishing fluid after a predetermined time interval. In accordance with the invention, this is accomplished by the provision of a timing device which includes a cylinder 50 and a contained piston 51. The piston rod 52 has an elongated portion 53 exteriorly of the cylinder 50 and in which is formed a slot 54. A pin 55 passes through the slot 54 and through a slot 56 in the handle 47 to pivotally connect the handle 47 and the piston rod 52. The slot 56 accommodates the relative movement of the pin 55 along the lever 47 due to the angular movement of the lever about the axis of the valve 46.

Piston 51 has an opening 57 therethrough and one side of it may be covered by the hinged flap valve 58. On the opposite side of the piston 51 from the flap valve 58 is a compression spring 59 which bears against the piston 51 and the opposing closed end of the cylinder 50.

An opening 60 is formed in one of the end walls of the cylinder 50 so that the movement of the piston 51 back and forth will create neither a suction nor a compression of air within this end of the cylinder. A like opening 61 is formed in the other end of the cylinder 50, but this opening is of relatively small size so that the passage of air therethrough will be greatly restricted.

When the valves are moved to the open position shown in Figure 4, the handle 47 is thrust in a left hand direction with respect to this figure. This moves the piston 51 toward the left and compresses the spring 59. Flap valve 58 is forced open by the compression of air in the end of the cylinder containing the spring 59 so that air can pass from this side of the cylinder to the piston rod side and little or no resistance will be offered to this movement of the piston by the entrapped air.

When the handle 47 is released, the spring 59 will exert a pressure against the piston 51 to push upon the piston rod 52 and thereby move the handle 47 toward the right in Figure 4 so as to close all of the valves. However, this movement will be retarded because the flap valve 58 will be moved to the position in which it closes the opening 57 through the piston 51. The air which is trapped in the piston rod end of the cylinder 50 can therefore only escape through the opening 61 in the end wall of the cylinder 50 and inasmuch as this opening is of very small size a considerable time period must elapse for the escape of this air. As a consequence, the valves will remain open for a relatively long period and this period can be increased or decreased by vary-

ing the size of the opening 61. To accomplish this variation in the size of opening 61, it may be formed in a replaceable plug 62.

When a fire is being approached, the attendant has merely to move the handle 47 to its valve opening position to cause the nozzle 13 and pipes 15 to be both supplied with their fire extinguishing mediums and to be set in motion. After a predetermined time the supply of fluid and the oscillations will be simultaneously stopped so that none of the fire extinguishing mediums will be wasted beyond the time that delivery is required. If an additional supply of the fire extinguishing mediums is necessary, the attendant has merely to move the handle 47 again to valve opening position. If he desires to shut off the supply of fire extinguishing mediums, and to stop the oscillations before the time at which stoppage would automatically be accomplished, the handle 47 can be moved to the valve closing position and this is permitted by the presence of the slot 54 in the piston rod 52.

It will be appreciated that it is not essential to employ both the carbon dioxide and the foaming material in conjunction with each other. The automatic oscillating means and the automatic shut-off means may be employed with a delivery only of carbon dioxide, or with a delivery only of the foaming material, or another fire extinguishing medium. However, best results are obtained if carbon dioxide and foam are employed together, because, as mentioned above, the foam not only helps to extinguish the fire, but forms a smothering blanket over the extinguished area.

If it is desired to not always cause the simultaneous operation of the valves 10, 19 and 46, they may be separately controlled by individual handles, as disclosed in Figure 6. For example valve 10 has the individual handle 63 attached to its operating stem 64, and valve 19 has the individual handle 65 attached to its operating stem 66.

The rate of oscillation may be varied by regulating the rate of supply of oil through the pipe 34. The angle through which the discharge nozzles are to swing may be adjusted, for example, by changing the radial distance the boss 21 is from the axis of pipe 12. It has been found that an arc of about 40° with a rate of oscillation of about one complete cycle every four seconds gives good results. With this arrangement, excellent coverage is obtained with a relatively low rate of discharge. The fire extinguishing medium is projected a considerable distance and thereby afford good protection for the advancing truck.

What I claim is:

1. Apparatus for delivering fire extinguishing medium comprising a discharge device, means pivotally mounting said device at a position close to the ground for oscillating movements about a vertical axis to thereby direct the discharge issuing from the device from side to side so that it will cover a relatively wide area, power operated means connected to said mounting means between said vertical axis and said discharge device for causing continuous side to side movements of the discharge device, a first valve for regulating the supply of power to the power operated means, a second valve for regulating the delivery of fire extinguishing medium to the discharge device, and manually actuated, spring loaded timing means for operating said first valve, acting after a predetermined time interval for closing said valve.

2. Apparatus for delivery of fire extinguishing medium comprising a discharge device, means pivotally mounting said device at a position close to the ground for oscillating movements about a vertical axis to thereby direct the discharge issuing from the device from side to side so that it will cover a relatively wide area, power operated means connected to said mounting means between said vertical axis and said discharge device for causing continuous side to side movements of the discharge device, a first valve for regulating the supply of power to the power operated means, a second valve for regulating the delivery of fire extinguishing medium to the discharge device, common means for operating said regulating valves, a pneumatic cylinder having a piston therein connected to said common means, resilient means urging said piston in the direction in which it serves to cause said common means to close said regulating valves, and means for restricting the exhaust of air from said cylinder under the action of said piston to thereby delay the valve closing movement of said common means.

3. Apparatus for delivering fire extinguishing medium comprising a discharge device, means pivotally mounting said device for oscillating movements about a vertical axis to thereby direct the discharge issuing from the device from side to side, fluid pressure operated means pivotally connected to said mounting means for causing continuous side to side movements of the discharge device, a first valve for regulating the supply of pressure fluid to the fluid pressure operated means, a second valve for regulating the delivery of fire extinguishing medium to the discharge device, common means for operating said regulating valves, and manually actuated, spring loaded timing means for operating said common means, acting to close the valves after they have been open for a predetermined length of time.

4. Apparatus for delivering fire extinguishing medium comprising a discharge device, means pivotally mounting said device for oscillating movements about a vertical axis to thereby direct the discharge issuing from the device from side to side, a double acting piston and cylinder connected to said mounting means for causing continuous side to side movements of the discharge device, a control valve for alternately delivering fluid pressure to and exhausting it from each side of the double acting piston, operating means for said control valve comprising a crank arm rigidly joined to the control valve, a rocker arm pivotally connected coaxially with said crank arm, resilient means connecting said crank arm and said rocker arm, means connecting said rocker arm and said mounting means so that oscillating movements of said mounting means are translated to said rocker arm, the oscillations of said rocker arm causing said resilient means to actuate said crank arm to cause automatic operation of said control valve, a valve to regulate the supply of fluid pressure to said control valve, and a separate valve for regulating the delivery of fire extinguishing medium to the discharge device.

5. Apparatus for delivering fire extinguishing medium comprising a discharge device, means pivotally mounting said device for oscillating movements about a vertical axis to thereby direct the discharge issuing from the device from side to side, a double acting piston and cylinder mounted for pivotal movement and pivotally connected to said mounting means for causing the action of said piston to impart continuous side

to side movements to the discharge device, valve means alternately delivering fluid pressure to and exhausting it from each side of the double acting piston, means operatively connecting said valve means to said mounting means to cause automatic operation of said valve means, a valve to regulate the supply of fluid pressure to said first-mentioned valve means, a separate valve for regulating the delivery of fire extinguishing medium to the discharge device, and common means for operating both of said regulating valves.

6. Apparatus for delivering fire extinguishing medium comprising a discharge device, means pivotally mounting said device for oscillating movements about a vertical axis to thereby direct the discharge issuing from the device from side to side, a double acting piston and cylinder, a piston rod on one side only of said piston extending from said cylinder for pivotal connection with said mounting means to cause continuous side to side movements of the discharge device, a control valve for alternately delivering fluid pressure to and exhausting it from each side of the double acting piston, means operatively connecting said control valve to said mounting means to cause automatic operation of said control valve, a valve to regulate the supply of fluid pressure to said control valve, a separate valve for regulating the delivery of fire extinguishing medium to the discharge device, and timing means acting after a predetermined time interval for closing the valve employed for regulating the supply of fluid pressure to said control valve.

7. Apparatus for delivering fire extinguishing medium comprising a discharge device, means pivotally mounting said device for oscillating movements about a vertical axis to thereby direct the discharge issuing from the device from side to side, a pivotally mounted double acting piston and cylinder connected to said mounting means at a point between said vertical axis and said discharge device for causing continuous side to side movements of the discharge device, a control valve for alternately delivering fluid pressure to and exhausting it from each side of the double acting piston, means operatively connecting said control valve to said mounting means to cause automatic operation of said control valve, a valve to regulate the supply of fluid pressure to said control valve, a separate valve for regulating the delivery of fire extinguishing medium to the discharge device, common means for opening said regulating valves, and timing means acting after a predetermined time interval for closing said regulating valves.

8. Apparatus for delivering fire extinguishing medium comprising a discharge device, means pivotally mounting said device for oscillating movements to thereby direct the discharge issuing from the device from side to side, a cylinder having a pivotally mounted closed end portion and an opening through the opposite end portion, a double acting piston within said cylinder having a piston rod extending through the opening at one end portion of the cylinder for connection with said mounting means to cause continuous side to side movements of the discharge device, a control valve for alternately delivering fluid pressure to and exhausting it from each side of the double acting piston, means operatively connecting said control valve and said mounting means to cause automatic operation of said control valve, a valve to regulate the supply of fluid pressure to said control valve, a separate valve for regulating the delivery of fire extinguishing

medium to the discharge device, timing means, and common means for opening said regulating valves and setting said timing means, said timing means acting after a predetermined time interval for returning said common means to the position for closing said regulating valves.

9. Apparatus for delivering fire extinguishing medium comprising a discharge device, means pivotally mounting said device for oscillating movements to thereby direct the discharge issuing from the device from side to side, a double acting piston and cylinder having a piston rod extending therefrom for pivotal connection with said mounting means to cause continuous side to side movements of the discharge device, a control valve for alternately delivering fluid pressure to and exhausting it from each side of the double acting piston, means operatively connecting said control valve and said mounting means to cause automatic operation of said control valve, a valve to regulate the supply of fluid pressure to said control valve, a separate valve for regulating the delivery of fire extinguishing medium to the discharge device, timing means, common operating means connected to said timing means and said regulating valves and operable for opening said regulating valves and setting said timing means, said timing means acting after a predetermined time interval for returning said common operating means to its position for closing said regulating valves, and means permitting the return of said common operating means to its position for closing said regulating valves independently of the operation of said timing means.

10. Apparatus for delivering fire extinguishing medium comprising a discharge device, means pivotally mounting said device for oscillating movements to thereby direct the discharge issuing from the device from side to side, a pivotally mounted double acting piston and cylinder, a piston rod connecting said piston to said mounting means for causing continuous side to side movements of the discharge device, a control valve for alternately delivering fluid pressure to and exhausting it from each side of the double acting piston, means operatively connecting said control valve and said mounting means to cause automatic operation of said control valve, a valve to regulate the supply of fluid pressure to said control valve, a separate valve for regulating the delivery of fire extinguishing medium to the discharge device, timing means, and common operating means connected to said timing means and said regulating valves and operable for open-

ing said regulating valves and setting said timing means, said timing means acting after a predetermined time interval for returning said common operating means to its position for closing said regulating valves, the connection between said timing means and said common operating means having a lost motion in one direction so that said common operating means may be returned to its position for closing said regulating valves prior to the complete actuation of said timing means.

11. Apparatus for delivering fire extinguishing medium comprising a discharge device, means pivotally mounting said device for oscillating movements to thereby direct the discharge issuing from the device from side to side, a double acting piston and cylinder mounted for pivotal movement and pivotally connected to said mounting means for the action of said piston to impart continuous side to side movements to the discharge device, a first valve for alternately delivering fluid pressure to and exhausting it from each side of the double acting piston, means operatively connecting said first valve and said mounting means to cause automatic operation of said first valve, a second valve to regulate the supply of fluid pressure to said first valve, a third valve for regulating the delivery of fire extinguishing medium to the discharge device, timing means, and common means connected to said timing means and the second valve and operable for opening said second valve and setting said timing means, said timing means acting after a predetermined time interval for returning said common means to its position for closing said second valve, the connection between said timing means and said common means having a lost motion in one direction so that said common means may be returned to its position for closing said second valve prior to the complete actuation of said timing means.
